(57) **CLAIM**

The ornamental design for a grappler tine, as shown and described.

DESCRIPTION

FIG. 1 is a left side elevational view of a grappler tine embodying my design, the right side elevational view being a mirror image thereof;

FIG. 2 is a top plan view of the grappler tine as shown in FIG. 1;

FIG. 3 is a bottom plan view of the grappler tine as shown in FIG. 1;

FIG. 4 is a rear elevational view of the grappler tine as shown in FIG. 1; and,

FIG. 5 is a front elevational view of the grappler tine as shown in FIG. 1.
